UNITED STATES PATENT OFFICE.

THOMAS J. FLAGG, OF NEW YORK, N. Y., ASSIGNOR TO FISK, CLARK
& FLAGG, OF SAME PLACE.

DESIGN FOR A MADE-UP SCARF.

SPECIFICATION forming part of Design No. 15,297, dated August 19, 1884.

Application filed May 3, 1884. Term of patent 7 years.

To all whom it may concern:

Be it known that I, THOMAS J. FLAGG, of the city, county, and State of New York, have invented a new and original Design for a Made-Up Scarf for Men's Wear, and I do hereby declare that the following is a full and exact description thereof, reference being had to the accompanying drawing, and to the letters of reference marked thereon, making a part of this specification.

My design involves the configuration of the outer apron, S, of the scarf as its prominent feature; and it consists, as represented in the drawing, of an irregular, compound, outward curve, A B C, whose upper portion, commencing at the neck-line of the scarf and bending outward, is described upon a radius which decreases progressively in length, and whose lower re-entrant portion is described upon a different radius, which increases progressively in length as the curve approaches the lower end of the scarf. This lateral compound-curve A B C is connected by a transverse lower line, C C', with an irregular line, C' E D A, which, commencing with an outward curve, C' E, bends thence inwardly in a straight or slightly-curved line, E D, which terminates at its intersection D, with an imaginary central line, x x, running lengthwise 3c of the scarf in the middle thereof, from which point D a second shorter straight line, D A, diverges with an increased inward inclination to the point of beginning at A. The outwardly-curved line C E is continued beyond the point E until it equals in length and conforms fully to the counterpart lower portion, B C, of the opposite outline of the outer apron, and then is merged into a second curve, B' A', described upon a radius corresponding to the radius of the upper portion, A B, of said outline, and with which it corresponds in length as well as in curvature. The upper ends of the two lateral curves, A B C A' B' C', are connected by the straight or slightly curved transverse line A A', which completes the outline and constitutes the top or neck

line of the complete scarf; and the curve A' B' E, in connection with said top line, A A', and with a straight line, A' D, which extends inwardly from the upper angle, A', to intersect the point D on the line E D A, define the outlines of the inner apron, T, and center piece, U, of the scarf.

The design may be ornamented and relieved of stiffness or flatness in appearance by means of folds, plaits, or puffs G G, extending inward from the upper portion, A B A' B', of the curved side lines, A B C A' B' C'.

I claim—

1. The design for a made-up scarf, herein shown and described, the same consisting of the lateral compound curve A B C, lower line, C C', and opposite lateral line, C' E D A, defining the contour of the outer apron of the scarf, in combination with the outline D E B' A' D, which, coinciding at D E with a portion of the outline of the outer apron, defines the contour of the exposed surface of the inner apron, and with the line A A', which, uniting the upper angles of the two aprons, constitutes the neck-line and completes the configuration of the entire scarf.

2. The design for a made-up scarf, herein shown and described, the same consisting of the lateral compound curve A B C, lower line, C C', and opposite lateral line, C' E D A, defining the contour of the outer apron of the scarf, the outline D E B' A' D, which, coinciding at D E with a portion of the outline of the outer apron, defines the contour of the exposed surface of the inner apron, the line A A', which, uniting the upper angles of the two aprons, constitutes the neck-line and completes the configuration of the entire scarf, and the ornamentation G G.

In testimony whereof I have signed my name to this specification in the presence of two subscribing witnesses.

THOMAS J. FLAGG.
